UNITED STATES PATENT OFFICE.

CONSUÈLO FOULD DE GRASSE, OF PARIS, FRANCE.

DESIGN FOR A CORSAGE-CORSET.

SPECIFICATION forming part of Design No. 34,234, dated March 19, 1901.

Application filed February 20, 1901. Serial No. 48,198. Term of patent 7 years.

To all whom it may concern:

Be it known that I, CONSUÈLO FOULD DE GRASSE, a citizen of the French Republic, residing at Paris, France, have invented and produced a new, useful, and original Design 5 for a Corsage-Corset, of which the following is a specification, reference being had to the accompanying drawing, forming a part of the same.

- 10 The drawing shows the corsage - corset opened or expanded, and it is composed of two parts—the back and the front. The back comprises the two like back-pieces *a a*, the two under-arm pieces *b b*, and the two hip-
15 pieces *c c*. The front comprises the upper pieces *d d*, with darts *e e*, the two lower outer pieces *f f*, and the two lower inner pieces *g g*. The upper pieces *d* are connected to the lower pieces *f* and *g* along a curved line *h*.
20 The main springs or bones of the corsage-

corset are indicated at *i*, and at *j* are bias bones or springs on the pieces *g*. Along the margins of the respective pieces are the busks or steels *k*.

The essential features of my design are the 25 contours of the upper pieces *d* and lower pieces *f g* of the front, the piece *g* extending up and running out at the armhole *m*, the curved lateral contour of the pieces *b*, and the contour of the back-pieces *a*. 30

I claim—

The design for a corsage-corset herein shown and described.

In witness whereof I have hereunto signed my name, this 7th day of February, 1901, in 35 the presence of two subscribing witnesses.

CONSUÈLO FOULD DE GRASSE.
